UNITED STATES PATENT OFFICE

HERBERT E. WHITE, OF CLEVELAND, AND WALTER F. SCHULZ, OF YOUNGSTOWN, OHIO,
ASSIGNORS TO TRUSCON STEEL COMPANY, OF YOUNGSTOWN, OHIO, A CORPORATION
OF MICHIGAN

DRAWING ROLL MECHANISM

Application filed February 8, 1930. Serial No. 426,986.

In drawing strips of different widths and gauges through cleaning and galvanizing apparatus, for economy's sake it is desirable that these strips be passing simultaneously through the various baths, etc., but this creates difficulty because the drawing rolls as ordinarily constructed, if spaced apart by the strips that are relatively thick, will not properly engage and carry along the thinner strips.

One of the objects of the present invention is to provide a simple, novel and effective drawing mechanism that will accommodate itself to strips of various widths and thicknesses and will properly operate on them, even when they are simultaneously passing through the apparatus.

An embodiment of the invention that is at present considered the preferable one is illustrated in the accompanying drawings, wherein:

Figure 1 is a front elevation of the drawing mechanism.

Figure 2 is an end elevation of the same.

Figure 3 is a view in elevation of the opposite end to that shown in Figure 2.

Figure 4 is a vertical cross sectional view on the line 4-4 of Figure 1.

Figures 5 and 6 are respectively sectional views on the lines 5-5 and 6-6 of Figure 3.

Figure 7 is a detail sectional view through one of the positioning rollers and its mount.

In the embodiment disclosed, a suitable base 8 is employed mounted on supporting beams 9 and carrying upstanding head plates 10 and 11. In these head plates is suitably journaled an upper drawing roll 12, which for the purpose of distinction is termed the main roll.

Beneath the roll 12 is a sectional drawing roll 13 coacting with the main roll 12. This lower roll includes a central shaft 14 having diametrically opposite wings or flanges 15, forming keys. Located on the shaft 14 and

16 individually movable laterally of the shaft and having internal keyways 17 that receive the keys 15. The width of the keys 15 is less than the depth of the keyways so as to permit the said lateral play of the drive collars. 50 Surrounding said drive collars 16 are sleeves constituting roll shell sections 18 that are also laterally movable with respect to the shaft and are keyed to the collars 16. To that end, said collars are provided in their peripheries 55 with keyways 19 that are disposed at right angles to the keyways 17 and in these keyways 19 are internal ribs 20 formed on the shell sections 18. It will be noted particularly by reference to Figure 4 that the keys 20 are of less width than the depths of their keyways 19 so that the shells are free to move laterally with respect to the shaft 14 and at right angles to the lateral movement permitted the drive collars 16. 60

Located beneath each shell section or sleeve 18 is a presser lever 21 fulcrumed at its rear end, as shown at 22 on a post 23 carried by the base 8. The free end of the lever is mounted on a depending vertically movable 70 plunger bolt 24 that passes through a supporting bar 25 and is yieldingly urged upwardly by a spring 26 having a bearing on the bar 25 and abutting a washer 27 adjustably fixed by nuts 28 to the upper end of the bolt 24. The portion of the lever 21 that passes beneath the shell section or sleeve 18 carries a bracket 29 in which are journaled 75 positioning and presser rollers 30 that bear against the under portion of the sleeve or shell section 18 on opposite sides of the central vertical plane of the axis of the shaft. It will be evident therefore that these rollers serve to prevent any horizontal lateral play on the part of the shell sections or sleeves 80 85 18, but will permit them to move vertically with respect to the roller 12 and against the tension of the springs 26.

Connecting the head plates 11 at the front side thereof, is a supporting bar 31 in which 80

guide pins 32 are detachably and adjustably mounted for directing the strips to be drawn by the rolls, between said rolls.

The rolls may be driven by any suitable means. Thus there is shown mounted on the base 8, a main drive shaft 33 geared at one end of the apparatus, as shown at 34 to a countershaft 35. This countershaft in turn through suitable gearing 36 drives the upper 10 main roll 12 and the lower sectional roll 13.

With this structure it will be evident that if a thin strip is entered between portions of the rolls 12 and 13, the lever or levers 21 acting on the shells or sleeves 18, which are engaged by the strip, will press the strip firmly against the main roll 12, and the said shells 18 will turn freely even though they are eccentric to the axis of the shaft 14. A thicker strip may be located alongside the thin strip 20 and so long as it is not engaged by the same shells or sleeves 18, it will not affect the drawing action thereon, but will hold the sleeves 18, which it engages, farther away from the main roll 12. Consequently it will be clear 25 that strips of various gauges and various widths may be engaged and drawn by the roll structure herein disclosed.

From the foregoing, it is thought that the 30 construction, operation and many advantages of the herein described invention will be apparent to those skilled in the art without further description, and it will be understood that various changes in the size, shape, proportion and minor details of construction, 35 may be resorted to without departing from the spirit or sacrificing any of the advantages of the invention.

What we claim, is:

1. In a drawing roll structure, the combination with a main bearing roll, of a coacting roll comprising a shaft, roll shell sections located end to end on the shaft, and laterally movable with respect thereto, drive members interposed between the shells and shaft and having laterally movable interlocking connections with both that permit both their lateral play and the lateral play of the shells, and means for urging the shells toward the main roll and permitting their individual movements away from the same while preventing their side play toward opposite sides of the main roll.

2. In a drawing roll structure, the combination with a main bearing roll, of a coacting roll comprising a shaft, roll shell sections located end to end on the shaft and laterally movable with respect thereto, drive members interposed between the shells and shaft and having laterally slidably interlocking connections with both that permit the lateral play of drive members and of the shells, and means for urging the shells toward the main roll and permitting their individual movements away from the same, said means holding the shells against lateral play

in directions transverse to said individual motions forward and from the main roll.

3. In a drawing roll structure, the combination with a main bearing roll, of a coacting roll comprising a shaft, a plurality of driving collars located on the shaft and interlocked therewith so as to have lateral play on the shaft, a plurality of roll shells surrounding the drive collars and interlocked therewith so as to have lateral play with respect to the shaft, the interlocking portions between the shells and collars being out of line with the interlocking portions of the shaft and collars, and means bearing against the shells for urging them toward the main roll.

4. In a drawing roll structure, the combination with a main bearing roll, of a coacting roll comprising a shaft, a plurality of driving collars located on the shaft and interlocked therewith so as to have lateral play on the shaft, a plurality of roll shells surrounding the drive collars and interlocked therewith, so as to have lateral play with respect to the shaft, the interlocked portions between the shells and collars being out of line with the interlocking portions of the shaft and collars, spring-pressed carrier arms at the side of the coacting roll opposite to the main roll, and spaced rollers on each of the arms bearing against the respective shells at spaced points to urge the shells toward the main roll and prevent their lateral displacement to either side of the same.

5. In a drawing roll structure, the combination with a main bearing roll, of a coacting roll comprising a shaft, a roll section, surrounding and located on the shaft, a drive member within the roll section and interposed between it and the shaft, said drive member having an interlocking drive connection with the shaft that effects its rotation by the shaft and permits it to move laterally with respect to the shaft and also having an interlocking drive connection with the roll section to effect its rotation and permit its lateral play with respect to the drive member.

6. In a drawing roll structure, the combination with a main bearing roll, of a coacting roll comprising a shaft, a roll section surrounding and located on the shaft, a drive member within the roll section and interposed between it and the shaft, a key and keyway connection between the drive member and shaft that secures their common rotation and permits the drive member to laterally play with respect to the shaft, and a key and keyway connection between the drive member and the roll section that secures their common rotation and permits the lateral play of the roll section with respect to the drive member.

7. In a drawing roll structure, the combination with a main bearing roll, of a coacting roll comprising a shaft, a roll shell sur-

rounding and located on the shaft, a drive sleeve surrounding the shaft within the roll shell, a key and keyway connection between the drive sleeve and shaft that secures their common rotation and permits the drive sleeve
5 to laterally play with respect to the shaft, and a key and keyway connection between the drive sleeve and the roll shell that secures their common rotation and permits the lateral play of the roll shell with respect to the
10 drive shell.

In testimony whereof, we affix our signatures.

HERBERT E. WHITE.
